UNITED STATES PATENT OFFICE.

ALBERT FRIEDRICH AND ROY O. POWELL, OF SAN ANTONIO, TEXAS.

DESIGN FOR AN ELECTRIC LAMP.

Application filed July 14, 1928. Serial No. 27,490. Term of patent 7 years.

To all whom it may concern:

Be it known that we, ALBERT FRIEDRICH and Roy O. Powell, citizens of the United States, residing at San Antonio, in the county of Bexar and State of Texas, have invented a new, original, and ornamental Design for an Electric Lamp, of which the following is a specification, reference being had to the accompanying drawing, forming part thereof.

In the drawings:—

Figure 1 is a front elevation.

Figure 2 is an end elevation.

Figure 3 is a top plan view.

We claim:—

The ornamental design for an electric lamp, as shown.

ALBERT FRIEDRICH.
ROY O. POWELL.
